NECKTIE HANGER

Ben B. Manaster, Chicago, Ill., assignor to Crest Specialty, Inc., Chicago, Ill., a corporation of Illinois

Filed Apr. 14, 1964, Ser. No. 79,492

Term of patent 7 years

(Cl. D80—8)

Fig. 1.

Fig. 2.

FIG. 1 is an elevational view of a necktie hanger showing my new design, the opposite side being a mirror image of the side shown;

FIG. 2 is an end elevational view taken from the right side as viewed in FIG. 1.

I claim:

The ornamental design for a necktie hanger, as shown and described.
